E. H. Hayes

Attorney

UNITED STATES PATENT OFFICE.

HARVEY C. HAYES, OF WASHINGTON, DISTRICT OF COLUMBIA.

FOLLOW-UP MECHANISM.

Application filed January 2, 1924. Serial No. 684,091.

To all whom it may concern:

Be it known that I, HARVEY C. HAYES, a citizen of the United States, and resident of Washington, District of Columbia, have 5 invented certain new and useful Improvements in a Follow-Up Mechanism, of which the following is a specification.

My invention relates to a means whereby the established position between two movable members may be maintained.

An object of the invention is to maintain a relative position between two rotatable members without the introduction of reacting torque.

15 A further object is to provide a mechanism as described that will be simple in construction and reliable in operation.

With the above and other objects in view the invention consists in the construction, 20 combination and arrangement of parts as will be hereinafter described.

Reference is to be had to the accompanying drawings in which like reference characters indicate corresponding parts throughout the several views, and in which—

25 Figure 1 is a vertical sectional view, and Figure 2 is a view on the line 2—2 of Figure 1.

As an example I have shown and will describe my invention as applied to a gyro-compass, although it will be understood that I do not limit myself to this particular application, as this mechanism may be used in connection with various devices.

30 Referring to the drawings, 1 and 2 indicate the gyro-wheel and supporting frame respectively of a gyro-compass and 3 and 4 the bearings about which the frame can turn on a vertical axis. Bearing 4 is hollow so that a stream of fluid can be forced 35 through it into a T-shaped member 5 supported by frame 2 and having two outlets 6 and 7. The fluid emerging from these outlets passes respectively into split nozzles 8 and 9, which direct the fluid stream to veins of two small turbine wheels 10 and 11. These turbines each operate a small pinion wheel 11^a and 12 through worm drives 13 and 14. The pinion wheels engage 40 in a circular rack 15 and are carried by a member 16 rotatable on bearing 17.

When outlets 6 and 7 of the member 5 are directly opposite split nozzles 8 and 9, the

fluid stream is accurately divided so that half emerges from each branch and under such conditions the two turbines will remain at rest, as the reaction of each branch is the same but in opposite senses with respect to turbine rotation. If the supporting frame is rotated slightly in a clockwise direction, the branch nozzles 8 and 9 will no longer equally divide the fluid stream issuing from member 5, but the lower branch of one will carry more of the fluid than will the upper, and the upper branch of the other will carry more than the lower branch. This will cause the two turbines 10 and 11 to rotate in an anti-clockwise direction and the pitch of the worm drives 13 and 14 is such that the action of pinion wheels 11^a and 12 cause member 16, which carries both turbines and both nozzles to be rotated in a clockwise direction about bearing 17. This motion will continue until the nozzles 8 and 9 are again brought opposite the outlets 6 and 7. The action, of course, will be the reverse if the frame is rotated in an anti-clockwise direction. It will, therefore, be seen that however frame 2 is rotated about the vertical axis, member 16 will, through the action of the two turbines operated through the split nozzles, be caused to follow this motion and that the follow-up motion is accomplished without the introduction of reacting torque on frame 2.

35 The algebraic sum of the reactions which the fluid stream sets up on frame 2 reduces to a force along the vertical axis and therefore introduces no torques about this axis. The directivity of the device is not affected by the fluid stream. If either of the two outlets 6 or 7 of member 5 is closed the sum total of the fluid reactions will then be along a line making an angle of 45° with the vertical axis but intersecting with it. This reaction will not introduce a torque tending to rotate the frame about its vertical axis but will introduce a side thrust on bearings 3 and 4. While closing one of the outlets does not affect the accuracy or sensitiveness of operation to any great extent, it is desirable to use both outlets.

40 It will be understood that the above description and accompanying drawings comprehend only the general and preferred embodiment of my invention and that various

minor changes in details of construction, proportion and arrangement of parts may be made within the scope of the appended claims and without sacrificing any of the advantages of my invention.

Having described my invention, I claim:

1. In a follow-up mechanism, a movable member, a fluid stream conductor having a plurality of outlets carried thereby, systems of gearing, a rotatable member, and means deriving motion from said fluid stream for imparting motion to said rotatable member through the gearing.
2. In a follow-up mechanism, a member movable on an axis, a fluid stream conductor having a plurality of outlets carried thereby, split nozzles opposite each of said outlets, systems of gearing, a rotatable member, and means deriving motion from said fluid stream for imparting motion to said rotatable member through the gearing.
3. In a follow-up mechanism, a member movable on an axis, a member rotatable in a plane at right angles thereto, systems of gearing, and co-acting fluid stream means carried by the respective members and directing a fluid stream against said gearing

to cause relative movement of said members through action of said gearing.

4. In a follow-up mechanism, a member movable on an axis, a member rotatable in a plane at right angles thereto, a stationary rack adjacent to the periphery of said rotatable member, a fluid stream conductor having a plurality of outlets carried by the movable member, split nozzles carried by the rotatable member, revolvable means carried by the rotatable member and co-acting with the conductor through said split nozzles, said means being rotated by a fluid stream passed therethrough, and means carried by the rotatable member and engaging with the rack and the revolvable means whereby movement is imparted to said rotatable member upon movement of said revolvable means.

5. In a follow-up mechanism, a freely movable member, a fluid stream conductor having a plurality of outlets carried by said movable member, a rotatable member and means deriving motion from said fluid stream carried by the rotatable member for imparting motion to said rotatable member.

HARVEY C. HAYES.
